United States Patent

Des. 235,685
Patented July 1, 1975

235,685

RIFLESCOPE

M. Gaines Chesnut, Denver, Colo., assignor to Outdoor
Sports Industries, Inc., Denver, Colo.

Filed June 24, 1974, Ser. No. 482,209

Term of patent 14 years

Int. Cl. D16—06

U.S. Cl. D57—1 E

FIG. 1

FIG. 2

FIG. 3

FIG. 4

FIG. 5

FIG. 1 is a perspective view of a riflescope showing my new design;

FIG. 2 is a side elevational view taken from either side of the riflescope of FIG. 1;

FIG. 3 is a top plan view thereof, the undisclosed bottom is a mirror image of the top;

FIG. 4 is an end elevational view thereof taken from one end of the riflescope of FIG. 1;

FIG. 5 is an end elevational view thereof taken from the other end of the riflescope of FIG. 1;

FIG. 6 is a perspective view of a modified embodiment of the riflescope illustrated in FIG. 1;

FIG. 7 is an end elevational thereof;

FIG. 8 is an end elevation taken from the side opposite FIG. 7;

FIG. 9 is a side elevational view of the modification;

FIG. 10 is a bottom plan view thereof; and

FIG. 11 is a top plan view thereof.

I claim:

The ornamental design for a riflescope, as shown and described.
